**AUXILIARY PROTECTIVE EXTENSION FOR
BASEBALL MASKS AND THE LIKE**

Frederick W. Glahe, La Grange, Ill., assignor to Wilson Athletic Goods Mfg. Co., Inc., River Grove, Ill., a corporation of Delaware

Filed July 12, 1960, Ser. No. 42,433
4 Claims. (Cl. 2—9)

This invention relates to an auxiliary protective extension for baseball masks and the like, and more particularly to an auxiliary extension attachable to the lower end portion of a face mask to afford protection for the wearer in the region of the neck and between the areas usually protected by the face mask and the chest protector.

One of the objects of my invention is to provide an auxiliary protective device which is readily attachable to a conventional baseball catcher's or umpire's face mask to extend the protection at the region of the wearer's neck and in an area normally left unprotected between conventional face masks and chest protectors.

Another object of the invention is to provide a rugged and relatively rigid auxiliary protective device which can be easily and quite quickly attached to the bottom portion of a face mask of the type used by catchers and umpires in the game of baseball, so as to afford a firmly supported downward extension of the face mask for the protection of the neck region of the wearer.

My invention has for another object the provision, in combination with a baseball catcher's or umpire's face mask, of a firm and relatively rigid extension supported in downward projecting relationship from the chin and lower jaw protecting portions of the mask.

As another object, this invention has within its purview the provision of an extension for the bottom of a face protective mask which includes a stiff and substantial outer shell having upper portions thereon for overlying outer surface regions of the face mask to provide support for the extension from the mask and having a lower mid-portion projecting downwardly from the upper portions thereof to a position well below the mask.

Other objects and advantages of the invention will be apparent from the following description and the accompanying drawings in which similar characters of reference indicate similar parts throughout the several views:

FIG. 1 is a perspective view of a mask of the type used by baseball catchers and umpires, which mask has attached thereto an auxiliary protective extension embodying a preferred form of this invention;

FIG. 2 is a fragmentary side sectional view of the invention taken substantially as indicated by a line 2—2 and accompanying arrows in FIG. 1;

FIG. 3 is a perspective view of my auxiliary protective extension for baseball masks and the like shown from the front side and detached from the mask;

FIG. 4 is a perspective view of the auxiliary protective extension shown from the back or inside thereof and detached from the mask; and

FIG. 5 is a side sectional view of the auxiliary protective extension taken substantially as indicated by a line 5—5 and accompanying arrows in FIG. 3.

In the exemplary embodiment of this invention which is depicted in the accompanying drawings for illustrative purposes, an auxiliary protective extension 10 is provided which is adapted to releasable securement to the lower

2

portion of a face mask 12 of the type used by baseball catchers, umpires and the like, and extends downwardly therefrom to afford protection for the wearer's neck. The usual masks worn by baseball catchers and umpires 5 protect the wearer's face and head, and separate chest protectors are used to protect the body of the wearer. However, the space between the chest protector and the face mask leaves the neck of the wearer exposed to possible injury by being struck by a ball, such as when a batter hits the ball with a glancing blow, commonly referred to as a "foul tip." The disclosed auxiliary protective extension 10 is releasably secured to, and extends downwardly from the mask 12.

As shown in FIG. 1, the mask 12 has an outer metal frame 13 including side portions 14 and 15, a bottom chin protecting portion 16, a top head protecting portion 17 and lateral cross members 18 and 19. In the disclosed structure, the outer frame and cross members are integrally cast of a light weight metal. The chin protecting portion 16 is curved from side to side so that the inner or back surface thereof is concave. A pad 20 extends across the inner surface of the chin protecting portion 16 and rests against the chin of a wearer to provide support for the mask when it is worn. In the disclosed structure, the pad 20 is removably secured to the chin protecting portion of the mask by tabs 22, 23, 24 and 25 at opposite ends of the pad and by tabs 26 and 27 at the mid-portion of the pad. The tabs 22 and 23 are secured to opposite edges of the pad 20, near one end thereof, and extend therefrom, while the tabs 24 and 25 are secured to the opposite edges of the pad near the other end thereof. The ends of the tabs 22 and 23 are releasably secured together by a fastening element, such as a snap fastener 28 with the tabs embracing the chin protecting portion of the mask in opposition to the pad. The tabs 24 and 25 embrace the chin protecting portion of the mask in opposition to the pad and are releasably secured together by fastening means, such as a snap fastener 29. Likewise, the tabs 26 and 27 embrace the mid-portion of the chin protecting portion in opposition to the pad 20 and are secured together by fastening means such as a snap fastener 30.

At the upper portion of the mask, a forehead engaging pad 32 extends across the inner or back surface of the cross member 18 to provide additional support for the mask when it is worn. This pad 32 has tabs 33, 34, 35 and 36 which are secured in pairs to opposite end portions of the pad 32 and have fastening means, such as snap fasteners 37 and 38 thereon for securing the respective pairs of tabs together in embracing relationship to the cross member 18 and in opposition to the pad 32. A pad 39 also extends across the inner or back surface of the head protecting portion 17 of the mask and is removably held in place thereon by tabs 40 and 42 which are secured to opposite edges of the mid-portion of the pad and are secured together by fastening means such as a snap fastener 43. The tabs 40 and 42 embrace the head protecting portion 17 of the mask in opposition to the pad 39. In use, the mask is held in place over a wearer's face and with the pads 20 and 32 engaging the chin and forehead respectively of the wearer by a head harness including adjustable strap elements 45 and 46.

My auxiliary protective extension 10, as shown in detail in the drawings, includes a relatively hard and rigid shell 47. This shell is relatively thin and is desirably

light in weight. Although it may be made of various materials, the shell 47 of the disclosed structure is made of a molded plastic material, such as a hard fiber. The shell 47 has a mid-portion 48 which is curved from side to side to conform generally to the curvature of the exterior surface of the chin protecting portion 16 of the mask. At the top, the mid-portion 48 of the shell has a marginal portion 49 which, in use, normally engages and rests against the lower marginal portion of the chin protecting portion 16 of the mask. Below the top marginal portion 49, the mid-portion of the shell extends downwardly well below the mask to serve as a neck protecting element for the wearer.

On opposite sides of the mid-portion 48 of the shell, integral wing portions 50 and 52 extend outwardly and somewhat upwardly, so that when placed in position against the chin protecting portion of the mask, the wing portions 50 and 52 overlie side portions of the mask frame structure. In the disclosed structure, the wing portions 50 and 52 adjoin the top and bottom edges of the mid-portion of the shell and are tapered toward their outer ends to widths commensurate with the opposite side portions of the chin protecting portion of the mask, which they normally overlie.

For firmly and releasably securing the shell in place on the mask, the opposite end regions of the wing portions 50 and 52 are embraced by the tabs 22 and 23 at one side of the mask and the tabs 24 and 25 at the other side of the mask, which tabs also hold the pad 20 in place against the inner surface of the chin protecting portion. Immediately below the top marginal portion 49 of the shell, a slot 53 is provided in the mid-portion 48 of the shell. The tab 27 extends through the slot 53 and connects to the tab 26 to embrace the top marginal portion of the shell to hold it in place against the outer surface of the chin protecting portion of the mask. In the disclosed structure, a corrugation 54 extends across the mid-portion of the shell below the slot 53 and is convex toward the forward or outer surface of the shell to rigidify the shell structure.

In the disclosed structure, a pad 55 extends across the inner or back surface of the shell 47 below the slot 53 and is releasably held in place by pairs of tabs 56 and 57 and 58 and 59 on opposite side portions of the pad. The tabs 56 and 57 are releasably secured together on the one side of the mid-portion of the shell by fastening means such as a snap fastener 62. The tabs 56 and 57 and the tabs 58 and 59 embrace the mid-portion of the shell in opposition to the pad 55.

As a result of the curvatures of the chin protecting portion of the mask and the shell, and since the wing portions 52 and 53 extend upwardly and outwardly from the mid-portion of the shell with the upper marginal portion of the mid-part of the shell and the outer ends of the wing portions embracing the front surface of the chin protecting portion of the mask, the shell affords a stable and relatively rigid downward extension of the mask for serving its protective function. In addition, the protective extension is readily attachable to and removable from a standard type of mask.

Having thus described my invention, what I claim as new and desire to secure by Letters Patent of the United States is:

1. In combination with a baseball catcher's mask or the like having a frame and guard bar structure including a bottom chin guard portion having an outer surface which is curved from side to side, a pad extending across the inner surface of said chin guard portion, and means including flexible tabs on said pad and embracing said chin guard portion at spaced positions for holding the pad in place, an auxiliary protective extension for the bottom of the mask comprising a formed shell of relatively thin, hard and stiff material which has a mid-

portion curved to conform generally to the curvature of the outer surface of said chin guard portion of the mask structure, said mid-portion of the shell having a top marginal portion engaging the outer surface of said chin guard portion and a portion extending downwardly a substantial distance below the chin guard portion, said shell also having side wing portions extending outwardly from opposite sides of the mid-portion thereof to positions overlying opposite side portions of said chin guard portion, and said flexible tabs on the pad embracing said side wing portions of the shell as well as the chin guard portion of the mask structure for holding the shell in place relative to the mask.

2. In combination with a baseball mask having metal frame and face protective parts including a laterally curved and vertically substantially straight chin protective part with pads secured against inner surfaces of some of the parts and including a chin pad having retaining tabs at the lateral mid-portion thereof and at the outer ends thereof for embracing the chin protective part for retaining thereof for embracing the chin protective part for retaining the pad in place, and said pads serving to support the mask relative to a wearer's face, an auxiliary protective extension comprising a relatively hard and rigid shell of generally uniform thickness and curved in contour from side to side to conform generally to the outer surface of said chin protective part, said shell having side wing portions which project upwardly and outwardly to opposite sides of an intervening mid-portion for engagement with spaced outer surface portions of said metal frame part of the mask, and said mid-portion of the shell having a mask frame engaging portion at the top thereof for engagement with the outer surface of said chin protective part and an opening therein through which one of said tabs at the lateral mid-portion of said chin pad projects to embrace said mask frame engaging portion of the shell, said wing portions of the shell being embraced by said tabs at the outer ends of the chin pad for further securing the shell to the mask frame, and said shell having thereon an integral portion extending downwardly therefrom to provide a neck protecting portion.

3. An auxiliary protective extension for baseball masks and the like having metal frame and face protective parts with pads secured against inner surfaces of some of the parts for supporting the mask relative to a wearer's face and comprising, in combination, a relatively hard and rigid shell of generally uniform thickness and curved in contour from side to side, said shell having side wing portions which project upwardly and outwardly to opposite sides of an intervening mid-portion for engagement with spaced outer surface portions of said metal frame part of the mask, and said mid-portion of the shell having a mask frame engaging portion at the top thereof and an integral portion extending outwardly therefrom to provide a neck protecting portion, said mid-portion of the shell having a tie receiving opening therein immediately below said mask frame engaging portion thereof for receiving a tie for holding the shell in place relative to said frame part of the mask.

4. An auxiliary protective extension for baseball masks and the like as defined in claim 3, and wherein said mid-portion of the shell has therein a stiffening corrugation of elongated contour extending laterally of the shell at a position below said frame engaging portion thereof.
